UNITED STATES PATENT OFFICE.

AXEL M. WALSTROM, OF MINNEAPOLIS, MINNESOTA.

MEANS FOR FACILITATING THE STARTING OF HYDROCARBON-ENGINES.

981,337.

Specification of Letters Patent. Patented Jan. 10, 1911.

Application filed August 19, 1910. Serial No. 577,949.

To all whom it may concern:

Be it known that I, AXEL M. WALSTROM, of Minneapolis, Hennepin county, Minnesota, have invented certain Improvements in Means for Facilitating the Starting of Hydrocarbon-Engines, of which the following is a specification.

My invention relates to devices for facilitating the starting of hydrocarbon engines and consists of means for relieving the compression in the engine cylinders and simultaneously priming said engine by injecting a combustible fluid into the cylinders or intake pipe.

My invention consists, generally, in combining the compression relief and priming devices and utilizing the air released from the cylinders by converting it into a combustible fluid and directing it back into the engine cylinders, either directly or through the intake pipe.

My invention consists, further, of various constructions and combinations as hereinafter described and particularly pointed out in the claims.

In the accompanying drawings forming part of this specification, Figure 1 is a side view of a four-cylinder engine with my invention applied thereto. Fig. 2 is a sectional view of one of the check valves shown in Fig. 1. Fig. 3 is a sectional view of the combined shut-off valve and atomizing nozzle also shown in Fig. 1. Fig. 4 is a side view of an engine similar to that shown in Fig. 1 but with a modified form of my invention applied thereto. Fig. 5 is a side elevation of another modification. Fig. 6 is a transverse sectional view of the distributing valve shown in Fig. 5. Fig. 7 is a sectional view on the line X—X of Fig. 6. Fig. 8 is a sectional view of the combined priming cup and valve shown in Fig. 5. Fig. 9 is a sectional view illustrating my invention applied to a single-cylinder engine. Fig. 10 is a sectional view of a combined check valve, shut-off valve and priming cup.

In the drawings 2 represents an engine crank case upon which the cylinders 3 are mounted. An intake pipe 4 connects said cylinder with a carbureter 5 having a gasoline supply pipe 6, through which a constant amount of gasoline is maintained in said carbureter. A check valve 7 is mounted on each cylinder and has a port 8 therethrough communicating with the interior of

said cylinders and adapted to be opened or closed by a ball 9. As shown in Fig. 1, a tube 10 has a connection with each of said check valves and with an atomizing nozzle 11 that has a threaded end 12 adapted to be screwed into a correspondingly threaded opening provided at any suitable point in the wall of the intake pipe 4. A port 13 extends through said nozzle and a perforated valve 14 is adapted to open or close said port and is provided with an arm 15 that is operated from any suitable point by a rod 16. Ports 17 and 18 connect the port 13 with a tube 19 that extends to, and communicates with, the gasoline supply in the carbureter 5. The valve 14 will normally close the port 13 and make my invention inactive, but when said valve is opened and the starting crank operated, the compressed fluid in the cylinders will flow through the check valves 7 into the tube 10 and through the atomizing nozzle 11 where it will draw gasoline through the ports 17 and 18 to become atomized and discharged therewith into the intake pipe where it is immediately drawn into a cylinder and consequently compressed and ignited.

In Fig. 4 I have shown, mounted on each cylinder, a combined check and shut-off valve 20 communicating with the interior of the cylinders and with a tube 21, each of these valves is connected to an operating rod 22 that is adapted to open or close all of said valves simultaneously. The tube 21 has an end 23 depending within a vertical pipe 24 which is adapted to contain a quantity of gasoline supplied through a tube 25 which is connected with the carbureter 5. A tube 26 connects the upper end of the pipe 24 with the engine intake pipe. When the valves 20 are opened and the engine starting crank is operated, the compressed fluid in the cylinders will be forced through the tube 21 into the gasoline in the lower part of the pipe 24 and thereby converted into a combustible fluid and discharged through the tube 26 into the engine intake pipe.

In Fig. 5 I have shown tubes 30, 31, 32 and 33 connecting each of the cylinders 34, 35, 36 and 37 with a distributing valve 38 having a perforated valve 39 adapted to simultaneously open or close the ports 40 communicating with the tubes 30, 31, 32 and 33. Balls 41 are provided in the ports 40 and adapted to open or close the ports 42 connecting the ports 40 with a longitudinal

port 43 that communicates with a carbureting device similar to that shown in Fig. 4 and referred to by the same reference numerals. Ports 44 lead from the ports 40 to 5 the ports 45 and are adapted to be opened or closed by balls 46. Ports 47 and 48 connect the ports 45 with a port 49 that communicates with a tube 50 which depends into the gasoline in the pipe 24. Assuming this to 10 be a four-cycle engine and the cylinders 34, 35, 36 and 37 performing, respectively, the compression, working, suction and exhaust stroke of the cycle while the starting crank is operated and the valve 39 being open to 15 allow a portion of the compressed fluid in the cylinder 34 to escape through the tube 30, port 40, ports 44 and 45, ports 47, 48 and 49 and tube 50 into the gasoline in the pipe 24 to be converted into a combustible fluid 20 and discharged through the ports 43, 42 and 40, and through the tube 32 into the suction cylinder 36 to mingle with and enrich the charge drawn in through the engine intake pipe and carbureter and consequently compressed and ignited to start the engine. 25

In Fig. 9 I have illustrated my invention applied to a single-cylinder engine 60 having an intake pipe 61 and an intake valve 62. A check valve 63 communicates with 30 the interior of the cylinder and is connected by a tube 64 with a combined shut-off valve and atomizing nozzle 65 that communicates with the intake pipe 61.

I do not wish to be confined to the construction and combinations shown and described, as my invention is capable of being modified in many ways without departing from its fundamental principle.

I claim as my invention, 35

40 1. Means for facilitating the starting of multiple-cylinder hydrocarbon engines, comprising, a compression relief device connected with each of said cylinders, means whereby the fluid released from the compressing cylinder is directed through a carbureting device into the sucking cylinder.

2. Means for facilitating the starting of multiple-cylinder hydrocarbon engines, comprising, a compression relief device con-

nected with each of said cylinders, means whereby the fluid released from the compressing cylinder is directed through a carbureting device into the intake passage of said engine.

3. Means for facilitating the starting of hydrocarbon engines, comprising, a compression relief device connected therewith, means whereby the fluid released from the compressing cylinder is directed through a carbureting device into the intake passage of said engine.

4. Means for facilitating the starting of hydrocarbon engines, comprising, a compression relief device connected therewith, means whereby the fluid released from the compressing cylinder is directed through a spraying or atomizing nozzle into the intake passage of said engine.

5. Means for facilitating the starting of hydrocarbon engines, comprising, a pressure relief valve connected with each cylinder of said engine, a passage connecting each of said relief valves, means for opening or closing said passage, a carbureting device connected with said passage, a passage connecting said carbureting device with the intake passage of said engine.

6. Means for facilitating the starting of multiple-cylinder hydrocarbon engines, comprising, a passage leading from each of said cylinders, means for simultaneously opening or inclosing said passages, a carbureting device connected with said passages, means whereby a portion of the fluid being compressed in one cylinder is released and directed through one of said passages into said carbureting device, and means whereby said released fluid is directed from said carbureting device through another of said passages into the cylinder in which the suction is taking place.

In witness whereof, I have hereunto set my hand this 17th day of August, 1910.

AXEL M. WALSTROM.
